UNITED STATES PATENT OFFICE.

ANTON LIJESKI, OF MILWAUKEE, WISCONSIN, ASSIGNOR OF ONE-HALF TO FRANK B. KANTORSKI, OF MILWAUKEE, WISCONSIN.

THERMOSTATIC VALVE.

Application filed June 15, 1925. Serial No. 37,359.

To all whom it may concern:

Be it known that I, ANTON LIJESKI, a citizen of the United States, and resident of Milwaukee, in the county of Milwaukee and State of Wisconsin, have invented certain new and useful Improvements in Thermostatic Valves; and I do hereby declare that the following is a full, clear, and exact description thereof.

10 This invention relates to thermostatic valves and is particularly directed to a valve adapted to be attached to a radiator.

Objects of this invention are to provide a thermostatic valve which will allow the exit 15 of air from the radiator but will prevent the passage of steam or water therefrom, and to provide a thermostatic valve which is devoid of diaphragms, expansible capsules, or similar members.

20 Further objects are to provide a thermostatic valve which is provided with a specially formed heated responsive metal member so constructed that it will provide a material amount of elongation for a relatively small 25 rise in temperature and to associate this member with a valve and float so that the valve will be actuated either by the member or by the float.

An embodiment of the invention is shown 30 in the accompanying drawings, in which:—

The single view is a vertical section through a thermostatic valve showing it detached from the radiator.

Referring to the drawings, it will be seen 35 that the valve comprises a base portion 1 which has an upwardly extending pipe 2 and a laterally projecting passageway of apertures 3. This passageway 3 is internally threaded and receives the nipple or similar fitting 4 whereby it may be attached to the radiator.

It is to be noted that the base portion is provided with a flange 5 which is externally threaded and receives the internally 45 threaded lower end of the casing 5. This flange is provided with a duct 7 which extends downwardly to the passageway 3.

It is to be noted that a curved siphon like pipe 8 extends loosely through the fitting 4 50 and to the passageway 3 so as to siphon out any water that may appear in the thermostatic valve, such water draining either through the aperture 7 or the pipe 2.

It is to be noted that the pipe 2 is pro-

vided with an enlarged portion 9 adjacent its 55 lower end to which the lower portion of a helical member 10 is secured by means of two or more screws 11. This helical member is spaced from the pipe 2 and extends upwardly within the casing 6. At its upper 60 end it is provided with a knurled or rounded portion 12 which receives a hub 13, such hub being rigidly secured in place by means of a screw 14.

It is to be noted that the helical member 65 10 is composed of two dissimilar metals so related that the member under the action of heat will materially elongate.

The casing 6 carries a top 14 which is provided with a valve seat 15. A valve 16 cooperates therewith to control the passage of air outwardly from the device. This valve is rigidly carried by means of a float 17. The float, it will be noted from the drawings, 70 is provided with a downwardly extending pin 18 which is loosely carried within a central aperture formed in the hub 13.

The operation of the apparatus is as follows:—When air collects within the radiator and fills the casing 6, the heated steam does 80 not act upon the helical member 10 and consequently such member is contracted. This positions the valve 16 away from the seat 15 and allows the air to escape. When, however, steam fills the casing 6, the helical 85 member expands and the valve closes thus preventing exit of steam. If the steam should condense or water collect within the valve casing, although the thermostatic valve may be open, nevertheless water will not 90 pass outwardly from the device, for the float 17 will rise as it is freely movable with respect to the hub 13, and will force the valve 16 into contact with the seat 15. However, water quickly drains from the valve due to 95 the loosely positioned siphon like pipe 7 and is discharged into the radiator.

It will be seen that the device does not depend for its operation upon any gas filled capsule, diaphragm or similar device, but 100 that it is extremely steady and reliable in its operation and obviously will have a long and efficient life.

It is to be noted particularly that the device is of very simple construction and is 105 relatively sturdy and rugged and is not likely to get out of order.

Although the invention has been described

in considerable detail, it is to be understood that the invention may be variously embodied and is, therefore, to be limited only as claimed.

I claim:

A thermostatic valve comprising a base portion having an upwardly extending apertured central pipe, said base portion having an aperture extending thereinto and adapted to communicate with a radiator, said base portion having a duct extending upwardly and communicating with said aperture, a casing extending upwardly from said base portion, a top carried by said casing and pro-

vided with a valve seat, a helical member 15 composed of two dissimilar metals secured to said base portion, and surrounding said upwardly extending pipe, a hub carried by the upper end of said helical member, a float loosely connected with said hub, and a valve 20 carried by said float and adapted to cooperate with said valve seat.

In testimony that I claim the foregoing I have hereunto set my hand at Milwaukee, in the county of Milwaukee and State of 25 Wisconsin.

ANTON LIJESKI.
